UNITED STATES PATENT OFFICE.

CHARLES G. LARSON, OF BURLINGTON, IOWA, ASSIGNOR OF ONE-HALF TO JOHN ELIASON,
OF MOLINE, ILLINOIS.

TRY-SQUARE.

No. 927,556.

Specification of Letters Patent.

Patented July 13, 1909.

Application filed July 21, 1908. Serial No. 444,581.

To all whom it may concern:

Be it known that I, CHARLES G. LARSON, a citizen of the United States, residing at Burlington, in the county of Des Moines and 5 State of Iowa, have invented new and useful Improvements in Try-Squares, of which the following is a specification.

This invention relates to foldable try squares, and the object of the invention is to 10 provide an accurate and reliable try square which may be readily folded into small compass whereby it may be readily fitted into the pocket of a mechanic and thus easily carried, the device being so constructed that it 15 may be readily unfolded to provide a square which shall be thoroughly accurate.

With these and other objects in view the invention resides in the novel construction and arrangement of parts hereinafter fully 20 described and claimed.

In the accompanying drawings, Figure 1 is a side elevation of a square constructed in accordance with the present invention. Fig. 2 is a similar view showing the device 25 folded. Fig. 3 is a transverse sectional view taken through the bolts at the upper portion of the device to illustrate the method of securing the blade when the device is set up. Fig. 4 is a transverse sectional view 30 upon the line 4—4 of Fig. 1 looking in the direction of the arrow.

In the accompanying drawings the numeral 1 designates the improved square. The square 1 comprises a handle member 2. The handle member 2 is constructed of a pair 35 of arms 3 and 4 suitably spaced apart at their upper ends through the medium of a spacing block 5 secured between the arms by a suitable bolt 6. The arms or members 3 and 4 have 40 their outer faces provided with rectangular cut away portions adapted to provide a gage when the square is employed upon sidings. Positioned between the arms 3 and 4 is a locking tongue 7. This tongue 7 is provided 45 with an inclined slot 8 adjacent its lower end and this slot is adapted for engagement with a suitable pin 9 connected with the members 3 and 4 of the handle 2.

Pivottally connected between the upper portions 50 of the members 3 and 4 as at 10 is the blade 11 member of the device. This blade member 11 is provided with a suitable depending portion or lug 12 upon its lower face adjacent its inner end, and this lug 12 is 55 adapted to be contacted by the upper edge

of the locking tongue 7 when the tongue is swung in the position illustrated in Fig. 1 of the drawings. When the blade 11 is set up as illustrated in Figs. 1 and 3, it will be noted that the squared spacing block 5 engages the 60 upper inner end of the blade, thus providing means whereby the blade is engaged upon this end as well as the tongue 7 contacting the lugs 12 and engaging the underface of the blade, thus effectively and securely locking 65 the blade in true position upon the handle.

When the device is to be knocked down or folded when not in use so as to be readily carried in the pocket of the mechanic, the mechanic grasps the blade 11 with one hand 70 and the tongue 7 with the other hand and swings the tongue upon its pivot 9 until it is entirely clear of the blade 11. The blade 11 may then be swung toward the handle 2 and the tongue 7 is revolved so as to complete a 75 circle. The tongue 7 is then drawn toward the bolt 6, this action being permitted by the inclined slot 8 engaging the member 9, and the blade 11 is then positioned upon the tongue 7 as clearly illustrated in Fig. 2 of the 80 drawing. When the parts are to be set up to form a square the operation just explained is reversed. The tongue 7 is pushed away from the bolt 6 causing the said tongue to ride upon the walls furnished by the inclined 85 slot 8 until the pintle 9 is positioned at directly the opposite end of the slot to that occupied when the device is folded. The blade 11 is swung upon its pivot 10 until its edge contacts the bolt 6 and the tongue 7 is 90 swung upon its pivot 9 until one of its ends engage the under edge of the blade 11 and its upper edges engages with the lug 12 of the blade, thus causing the device to assume the position illustrated in Fig. 1 of the drawing. 95

From the above description, taken in connection with the accompanying drawings, it will be noted that I have provided an extremely simple, cheap and effective knock down or collapsible try square, one which may be easily and quickly set up to form a perfectly true square or which may be readily collapsed to be carried in the pocket of a mechanic. The blade 11 of the square is provided with suitable graduations indicating a foot rule, and the device may be readily employed for measuring when in its knock down position. The longitudinally extending cut away portion of the members 3 and 4 provides an effective gage. 105 110 115

When it is desired to square a siding to a window or door frame, the siding may be placed partly upon the same, and a part thereof to rest upon a suitable support but in 5 a common plane with respect to the frame, and the gage set upon the siding to rest at each end against the frame that the siding is to fit, and by marking along the side of the gage next to the frame, it is obvious that 10 said siding may be correctly cut.

Having thus fully described the invention what is claimed as new is:

1. A foldable try square comprising a handle formed of a pair of spaced members, 15 a spacing block between the members at their upper ends, a blade pivotally connected between the members and adapted to contact the spacing block, and a locking tongue pivotally connected between the members 20 and adapted to be swung into engagement with the blade.

2. A foldable try square comprising a handle formed of a pair of spaced members having their outer edges provided with a rectangular cut away portion, a spacing 25 block between the members at their upper ends, a blade provided with a depending lug pivotally connected between the members and adapted to contact the spacing block, and a locking tongue provided with an inclined slot pivotally engaged between the members of the handle and adapted to contact the under face of the blade and engage the vertical wall of the depending lug when the device is set up. 30

In testimony whereof I affix my signature in presence of two witnesses.

CHARLES G. LARSON.
